UNITED STATES PATENT OFFICE

PETER T. B. NEVIUS, OF FLEMINGTON, NEW JERSEY, ASSIGNOR OF ONE-HALF TO ANDREW T. CONNET, OF FLEMINGTON, NEW JERSEY.

SKIRT-HANGER.

No. 833,693.

Specification of Letters Patent.

Patented Oct. 16, 1906.

Application filed July 12, 1905. Serial No. 269,399.

To all whom it may concern:

Be it known that I, PETER T. B. NEVIUS, a citizen of the United States, residing at Flemington, in the county of Hunterdon and State of New Jersey, have invented new and useful Improvements in Skirt-Hangers, of which the following is a specification.

This invention relates to skirt-hangers.

The principal objects of the invention are to improve and simplify the construction of such devices; furthermore, to increase their efficiency in use and to decrease the expense attending their manufacture.

A further object of the invention is to combine the improved skirt-hanger of this invention with an ordinary form of coat-hanger.

With the foregoing and other objects in view, which will appear as the description proceeds, the invention resides in the combination and arrangements of parts and in the details of construction hereinafter described and claimed as a practical embodiment thereof.

In the accompanying drawings, forming part of this specification, Figure 1 is a view in elevation of a skirt-hanger constructed in accordance with the invention. Fig. 2 is an enlarged detail view of one of the skirt-engaging members. Fig. 3 is a view, similar to Fig. 1, of a modified construction.

Like reference characters indicate corresponding parts in the different figures of the drawings.

The reference-numeral 1 indicates an ordinary curved coat-hanger having the usual hook 2. The coat-hanger 1 preferably is formed adjacent to the opposite ends thereof with notches, such as 3, although these notches are not absolutely essential and may be dispensed with, if desired.

The reference-numeral 4 indicates a skirt having an ordinary skirt-band 5, which is adapted to be supported by a pair of skirt-engaging members A and B. The skirt-engaging members A and B preferably are of such construction as to be automatically locked in adjusted position upon the coat-hanger 1 when a skirt is engaged therewith, as shown in the drawings. Each of the skirt-engaging members A and B preferably is formed of wire, and comprises a depending arm 6, having a bent portion 7 at the lower end thereof. This portion 7 may be bent in

different ways, if desired, as indicated in Figs. 1 and 3 of the drawings. The straight portion of the depending arm 6 is adapted to engage the skirt-band 5, as shown in the drawings, and the bent portion 7 is adapted to prevent the skirt-band from slipping downward upon the depending arm. In addition to the depending arm 6 each of the skirt-engaging members is formed with a pair of loops 8 and 9, the loop 8 completely surrounding the coat-hanger 1 and the loop 9 being open at its lower end, as shown, and having the terminal end thereof bent to form a handle portion 10.

It will be apparent from Fig. 1 that when the skirt-band 5 is engaged with the depending arms 6 of the two skirt-engaging members A and B and said skirt-engaging members are moved away from each other upon the coat-hanger 1 the tendency of the skirt-band 5 to draw the two depending arms 6 toward each other causes the upper portion of the loop 9 on each skirt-engaging member to bite or fit into one of the notches in the upper edge of the coat-hanger 1, whereby the two skirt-engaging members are automatically locked in adjusted position by the action of the skirt-band.

When it is desired to release the skirt, the handle portion 10 of one or the other of the skirt-engaging members is pushed upward by the thumb or hand, so as to cause the upper portion of the loop 9 to become disengaged from the notch in which it is seated. It will be observed from Fig. 1 that the handle portion 10 of the skirt-engaging member A is disposed on the side of the coat-hanger 1 opposite to the handle portion 10 of the skirt-engaging member B. For this reason the skirt can be disengaged from the hanger by a person standing on either the front or the rear side thereof.

The construction illustrated in Fig. 3 is the same as that shown in Figs. 1 and 2, except that the coat-hanger or "supporting member" 1, as the same will be termed in the following claims, is straight instead of curved. This construction is more inexpensive than that illustrated in Fig. 1.

The improved device of this invention is strong, simple, durable, and inexpensive in construction, as well as thoroughly efficient in operation.

Having thus described the invention, what is claimed as new is—

1. A skirt-hanger comprising a support, and a plurality of skirt-engaging members 5 slidably mounted thereon, each of said skirt-engaging members being formed of wire and comprising a depending arm having a bent portion at the lower end thereof, and a pair of loops engaging the supporting member, one 10 of said loops being open at its lower end, and having the terminal portion thereof bent to form a handle.
2. A skirt-hanger comprising a support and a plurality of skirt-engaging members 15 slidably mounted thereon, said skirt-engag-

ing members being adapted to be automatically locked in adjusted position when a skirt is engaged therewith, each of said skirt-engaging members being provided with a handle portion, and the handle portion of one 20 of said skirt-engaging members being located on the side of the support opposite the handle portion of the other skirt-engaging member.

In testimony whereof I have affixed my 25 signature in presence of two witnesses.

PETER T. B. NEVIUS.

Witnesses:

JUDIAH HIGGINS,
H. H. RITTENHOUSE.
